MEANS FOR MAKING COATED ROD-LIKE ARTICLES

John N. Whitehouse, New York, N. Y.

Application November 24, 1933, Serial No. 699,549

10 Claims.

(Cl. 18—3)

This invention relates to improvements in means for and methods of making coated rod-like articles, and more particularly to means for and methods of applying strips or ribbons of cellulose material in spiral fashion to a rod-like core.

In the manufacture of rod-like articles, such as fountain pen barrels, umbrella handles, and the like, it has been customary to construct the article of laminated material for the reason that some types of materials are considerably more expensive than other types. Consequently, cheaper materials have been used as the cores of the articles, and more expensive materials as the outer coats of such articles. Various methods have been used for applying coats of expensive material to cores, but such methods have involved objectionable features, such as difficulty to operate and the expense involved in the manufacture.

An object of the present invention is to provide new and improved methods for wrapping a strip or ribbon of cellulose material about a core.

Another object of the invention is to provide methods for so wrapping a strip of material about a core as to have the material therearound in spiral fashion.

Another object of the invention is to provide methods for wrapping a strip of material in spiral fashion about a core and simultaneously so securing the strip to the core that a finished article presents a substantially homogeneous structure.

A further object of the invention is to provide means for carrying the method of coating a core set forth hereinbefore.

A further object of the invention is to provide means for rotating a core together with a tool for feeding strip material to the core to be wrapped therearound, so that the finished article has a spiral coating of strip material therearound.

A still further object of the invention is to provide a tool for the use stated, of such character that wrapping of the strip material about the core is accomplished at uniform rate and cementing of the strip material to the core is accomplished simultaneously with the wrapping.

In carrying out the present invention, use is made of a suitable machine for rotating a core. Such machines may be any one of many characters so long as it provides means for rotating a core together with means for advancing a combined core supporting means and solvent container supporting means as the core is rotated. The rotation means may, if desired, include re-

verse mechanism for returning the core and solvent container supporting means back to the original position after a core has been wrapped. The core supporting means which moves as the core is rotated, consists of a member having an opening therein, which opening is coaxial with the power member utilized for rotating the core. In addition to this opening, the supporting member may be provided with a table on which can be mounted a container for solvent.

In conjunction with the core rotating mechanism and movable supporting member, use is made of a tool, the operation of which is partially automatic and partially manual. This tool consists of a handle to one end of which is secured an enlargement hollowed out for the major portion to an internal diameter substantially the same as the external diameter of the core which is to be wrapped. At one end the bore is provided with an angularly extending termination, and the tool is provided with a semi-tubular seat adjacent this angular termination, such seat being of a radius greater than that of the bore by an amount equal to the thickness of the strip of material to be wrapped around the core. The shoulder between the bore and the seat forms a guide for aligning the strip as it is fed into position to be wrapped around the core. The strip itself is fed along the length of the handle, and in order that proper tension may be applied to the strip as it is wrapped around the core, a frictional tension member which presses the sheet to the handle is provided. Spaced from the bore at the end of the handle is an adjustable guide member which serves to align the strip along the handle as it is fed into wrapping position.

A conduit for supplying solvent to the strip immediately prior to its contact with the core is connected to the solvent container on the movable supporting member, preferably by means of a flexible tube. In order that the flow of solvent can be accurately controlled, a stop member is provided on the underside of the handle in such position that it can engage the flexible tube and compress the same to such an extent as to cut off the supply of solvent to the supply nozzle which is fastened rigidly to the handle. A spring normally forces this member into position compressing the tube. This tool can be designed to be held manually during the operation, or if desired, suitable arrangements can be made for supporting the tool movably along with the travelling supporting member. The control of the supply of solvent is preferably of a manual char-

acter, but this construction naturally is not essential.

The strip material used to coat cores in accordance with the present invention, may be of suitable cellulose material; by which is meant nitrated or acetated cellulose material, or similar material. Throughout the specification and claims wherein the term rod-like article or core is used, it is to be understood that this term refers to cores or articles which may be hollow or which may be solid and which may have cylindrical exteriors or exteriors of other suitable configurations. Furthermore, the core may be made of a cellulose material if desired, or in some instances, it will be advantageous for the core to be made of wood or of metal, or of any other suitable material. When the core is made of some cellulose material, the strip when wound thereupon will be so secured to the core due to the use of a solvent that a substantially homogeneous structure is formed as a finished article. When the core is of such material that the solvent will not act thereupon, the spiral strip will still be secured thereto due to the flowing together of the edges of the spiral following the application of a solvent, and also by the shrinkage of the strip around the core after the solvent dries.

Other features, objects and advantages of the invention will become apparent by reference to the following detailed description read in conjunction with the accompanying drawings which form a part of the same, wherein

Fig. 1 is an elevation of a suitable form of mechanism for rotating a core with the tool of the invention shown in position to be used in wrapping a strip of material around the core.

Fig. 2 is an enlarged plan view of the tool in position to accomplish the wrapping of the sheet about the core.

Fig. 3 is a section taken substantially on the line 3—3 of Fig. 2.

Fig. 4 is a section taken substantially on the line 4—4 of Fig. 2.

Fig. 5 is a bottom view of the tool.

Fig. 6 is a section taken substantially on the line 6—6 of Fig. 3 with the core and strip omitted.

Referring now to the drawings, 10 indicates generally mechanism for transferring power from a motor 11 to a rotatable driving member 12 and a rotatable screw member 14. Mechanism 12 is supported upon a base 15 and a supplemental base 16 cooperates therewith to support operating parts thereof. Inasmuch as the particular mechanism indicated at 10 and including gearing of various types forms no part of the present invention, it is not illustrated in detail herein. The only requirement is that the rotating head 12 be driven simultaneously with the rotating screw 14. A handle 17 serves to control the direction of rotation of the screw 14.

Extending between the base 15 and the base 16 are guide rods 18. The rods 18 pass through the bottom 19 of a supporting member 20. A portion 21 of the supporting member is hollowed out and internally threaded for the reception of the screw 14. The supporting member 20 extends upwardly to a point above the axis of the rotatable member 12 and is provided with a platform or table 22 and with a vertical plate 24 having an opening 25 which is coaxial with the rotatable member 12. Table 22 serves as a support for a solvent container 26.

The end of the rotatable member 12 is hollowed out as shown in Figure 1 for the reception of

one end of a rod-like member or core 27. Diametrically opposite openings are provided in this member 12 through which pass a pin 28 which also passes through the end of the core 27.

In conjunction with the power mechanism described, use is made of a tool indicated generally at 30. This tool is in the nature of a flat strip of material, preferably metal, one end of which is shaped to provide a handle 31. The other end of the member 30 is provided with a depression 32 extending across the end in an angular direction. Securely but removably fastened in the depression 32 is a guide member indicated generally at 34, part of said guide member being in the nature of a tube 35 having a bore of such diameter as to fit snugly around the core 27. The remaining part of the member 34 is of semi-tubular form as indicated at 36. The tube 35 is cut off at right angles to the axis thereof as at 37, down to the top edges of the semi-tubular part 36. However, the semi-tubular portion 36 is provided with a part 38 of the same radius as the tubular portion 35, which part 38 terminates in an angular shoulder 39 as shown clearly in Figure 2. The remainder of the semi-tubular portion 36 has an internal radius slightly greater than the radius of the tubular portion 35, the difference in radii of these two parts being approximately equal to the thickness of the strip of material to be wound upon the core. This shoulder 39 serves as a guide for aiding in fitting the strip into position to be wound spirally around the core.

A plate-like guide member 40 is provided with a slot 41 through which passes a set screw 42 threaded into the handle 30. One end of the member 40 is substantially U-shaped as at 44 to overlie one edge of a strip or ribbon 45 which passes over the member 40, when it is fed into wrapping position. By means of the slot 41 and the set screw 42, the position of the guide member 40 can be adjusted. Pivottally secured to the tool 30 by means of a bolt 46 is a tension member 47 having an arm 48 and a handle 49. The arm 48 is so constructed and attached to the member 30 as to be forced towards the upper surface of this member 30. Pins 50 are so secured to the arm 48 that the heads thereof will bear against the strip or ribbon 45 when the arm is in position shown in full lines in Figure 2.

A solvent supply tube 55 has a portion thereof secured beneath the member 30 by means of a clip 56, and has another portion which passes through the member 30 at 57 and extends in circular form as at 58 to a position where it will discharge solvent upon this strip or ribbon 45 from the discharge end 59. The tube 55 which is preferably made of some metal, is connected to the solvent container 26 by means of a flexible conduit 60 which may be made of some suitable material, such as rubber, and which is of suitable length. In order that the flow of solvent from the container to the discharge opening of the rigid tube 55 may be controlled, use is made of a simple cut off arrangement which consists of a lever 61 pivotally secured to the underside member 30 as at 62. One end 64 of the lever 61 is so shaped and of such size as to be able to bear against the flexible tube 60 as shown clearly in Fig. 5. The other end 65 of the lever 61 is shaped into a handle which is normally forced away from the handle 31 by means of a spring 66. When the handle 65 is forced away from the handle 31 as shown in Fig. 4, the end 65 of the lever 61 so compresses

the flexible tube 60 as to cut off the flow of solvent from the container to the discharge end 59.

The operation and use of the mechanism and the tool described is substantially as follows:

- 5 With the rotatable member 12 stationary and with the supporting member 20 in position near thereto, a core 27 is passed through the opening 25 and then through the bore 35 of the tool 38. One end of a strip or ribbon 45 is secured to the 10 end of the core 27 by passing the pin 28 through the ribbon and through the core, which manoeuvre at the same time fastens the core and strip to the rotatable member 12. The strip is passed around the core and between the core and the seat provided by the semi-tubular member 36. The strip 15 then extends along the tool passing the handle 31 in which position it is held by moving the tension arm 48 from the dotted line position of Figure 2 to the full line position of the same 20 figure.

Power is then applied to rotate the member 12 and to simultaneously rotate the screw 14. Rotation of the member 12 causes rotation of core 27, which latter rotation draws the strip 45 under 25 the brake arm 48 into the seat 36 and around the core 27 in spiral fashion. As the winding operation begins, the operator presses the handle 65 toward the handle 31, thereby permitting the flow of solvent from the container out of the discharge 30 opening 59 and onto the strip 45. As will be seen, this discharge opening is so positioned that solvent is applied to the strip immediately prior to its contact with the core. As a result of such application of solvent, the strip which is preferably 35 of some cellulose material, either nitrated or acetylated, or any similar preparation, becomes slightly plastic with the result that the contacting edges of the spiral flow together, and if the core 27 is of cellulose material, the strip and the 40 core also flow together. As the rotation continues, the supporting member 21 moves outwardly along the core 27 which is supported by the plate 24 through which it passes. This movement, of course, carries the solvent container in 45 the same direction. If the tool is held manually by the operator, it will be seen that the close fit between the core and the bore 35 and between the coated core and the seat 36 will result in the tool moving along the core as the core is rotated.

50 Correct positioning of the strip around the core during the winding operation is assured by the shoulder 39, which is of such angularity as to cause a close spiral wind to be made. This angularity depends upon the width of the strip and 55 upon the size of the core being covered. As before stated, the variation in radii between that of the bore 35 and that of the seat 36 is substantially equal to the thickness of the strip 45, so that as the strip passes under the core and between the 60 core and the seat, it is firmly pressed against the core to correctly fasten it thereto. The tension arm 48 which really acts as a brake, serves to keep the strip under tension as it is wound around the core, so that no wrinkles will be formed in 65 the spiral.

The guide member 40 naturally can be adjusted to accommodate various widths of strips, and it is contemplated that the unitary bore 35 and seat 36 can be detached from the tool at any desired time so that other unitary structures of similar character but different dimensions can be fastened thereto to accommodate cores of different size. In the embodiment illustrated, the solvent discharge is shown as being so positioned as 70 to permit the application of solvent directly to 75

the ribbon before the ribbon contacts with the core. Naturally, the discharge opening could be positioned to apply the solvent directly to the core instead of to the ribbon if desired, or directly onto both the strip and core immediately prior to their contact. The same results will be produced.

At the completion of the winding operation, the guide plate 24 passes beyond the end of the core 27; almost concurrently with which the ribbon 45 10 is completely wrapped around the core. Power is cut off, the flow of solvent is cut off by releasing handle 65, and the tool is disengaged from the core and then the completed coated rod-like member can be removed from the hollowed part 15 of the rotatable member 12. The mechanism can then be reversed by manipulation of the handle 17 to move the supporting member 20 back to initial position. When it reaches this position, another core and another strip can be inserted in operative position and the process completed.

The tool shown is one which is designed primarily to be operated manually, that is, it is held by the operator during the winding of the strip 25 around the core. It will be apparent, however, that this tool could be supported by the supporting member 20 very readily and be carried by this member 20 as it advances along the core.

From the foregoing it will be seen that the 30 present invention provides a novel method of coating rod-like articles with strip cellulose material, and also provides apparatus for carrying out this method with maximum simplicity. By 35 practicing this method with the apparatus disclosed, it is possible to produce rod-like articles coated with strip cellulose material, which articles may be hollow or solid as desired, and which may have cylindrical exteriors or exteriors of other configuration as occasion may demand. In 40 view of the evident modifications which can be carried out without departing from the spirit of the invention, it is to be understood that this invention is not to be limited by the illustrated embodiments, but it is to be limited only by the 45 scope of the following claims.

I claim:

1. Apparatus of the type described comprising mechanism for rotating a core, means for securing one end of a strip of coating material to one end of the core, and a tool for guiding said strip to said core in such fashion that the strip is wrapped spirally tightly around the core as the core is rotated, said tool having a bore fitting snugly around the core and having an angular shoulder at one end of the bore to position the strip relative to the core as they contact.

2. Apparatus of the type described comprising mechanism for rotating a core, means for securing one end of a strip of coating material to one end of the core, a tool for guiding said strip to said core in such fashion that the strip is wrapped spirally tightly around the core as the core is rotated, said tool having a bore fitting snugly around the core and having an angular shoulder at one end of the bore to position the strip relative to the core as they contact, and a semi-tubular seat adjacent said shoulder for smoothing said strip as it passes over the seat and under the core.

3. Apparatus of the type described comprising mechanism for rotating a core, means for securing one end of a strip of coating material to one end of the core, a tool for guiding said strip to said core in such fashion that the strip is

wrapped spirally tightly around the core as the core is rotated, said tool having a bore fitting snugly around the core and having an angular shoulder at one end of the bore to position the strip relative to the core as they contact, and means for applying an adhesive prior to the contact of a strip with the core to bind the strip to the core.

4. Apparatus of the type described comprising mechanism for rotating a core, means for securing one end of a strip of coating material to one end of the core, a tool for guiding said strip to said core in such fashion that the strip is wrapped spirally tightly around the core as the core is rotated, said tool having a bore fitting snugly around the core and having an angular shoulder at one end of the bore to position the strip relative to the core as they contact, and means carried by said tool for applying tension to the strip as it is wrapped around the core.

5. Apparatus of the type described comprising mechanism for rotating a core, means for securing one end of a strip of coating material to one end of the core, a tool for guiding said strip to said core in such fashion that the strip is wrapped spirally tightly around the core as the core is rotated, and a solvent deliverer carried by said tool and having its discharge opening positioned to discharge solvent onto said strip prior to its contact with the core.

6. Apparatus of the type described comprising mechanism for rotating a core, means for securing one end of a strip of coating material to one end of the core, a tool for guiding said strip to said core in such fashion that the strip is wrapped spirally tightly around the core as the core is rotated, a core support movable along the core as it rotates, a solvent container on said support, and a solvent discharge member carried by said tool and connected to said container.

7. Apparatus of the type described comprising mechanism for rotating a core, means for securing one end of a strip of coating material to one end of the core, a tool for guiding said strip to

said core in such fashion that the strip is wrapped spirally tightly around the core as the core is rotated, a core support movable along the core as it rotates, a solvent container on said support, a solvent discharge member carried by said tool and connected to said container, and means for controlling the discharge of solvent.

8. Apparatus of the type described comprising mechanism for rotating a core, means for securing one end of a strip of coating material to one end of the core, a tool for guiding said strip to said core in such fashion that the strip is wrapped spirally tightly around the core as the core is rotated, a core support movable along the core as it rotates, a solvent container on said support, a solvent discharge member carried by said tool and connected to said container, and means carried by said tool for applying tension to the strip as it is wrapped around the core.

9. Apparatus of the type described comprising mechanism for rotating a core, means for securing one end of a strip of coating material to one end of the core, a tool for guiding said strip to said core in such fashion that the strip is wrapped spirally tightly around the core as the core is rotated, means for applying an adhesive prior to the contact of the strip with the core to bind the strip to the core, and an adjustable guide member carried by said tool for guiding said strip along the tool.

10. Apparatus of the type described comprising mechanism for rotating a core, means for securing one end of a strip of coating material to one end of the core, a tool for guiding said strip to said core, in such fashion that the strip is wrapped spirally tightly around the core as the core is rotated, and a solvent discharge member having its discharge orifice maintained in position to discharge flowing solvent directly onto at least one of the parts being assembled immediately prior to the contact being established between the core and the strip.

JOHN N. WHITEHOUSE.
